(57) **CLAIM**

The ornamental design for a collapsible liquid storage device with integral resealable drinking means, as shown and described.

DESCRIPTION

FIG. 1 is a perspective view of a collapsible liquid storage device with integral resealable drinking means showing my new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken line showing of a handle in FIG. 1 is included for the purpose of illustrating environmental structure and forms no part of the claimed design.
